UNITED STATES PATENT OFFICE.

WILLIAM E. BERTRAM, OF BROOKLYN, NEW YORK, ASSIGNOR TO INTERNATIONAL TYPESETTING MACHINE COMPANY, OF NEW YORK, N. Y., A CORPORATION OF NEW YORK.

LINE-CASTING MACHINE.

1,153,020.

Specification of Letters Patent. Patented Sept. 7, 1915.

Application filed January 20, 1913. Serial No. 743,186.

To all whom it may concern:

Be it known that I, WILLIAM E. BERTRAM, a citizen of the United States, residing at Brooklyn, in the county of Kings and State 5 of New York, have invented new and useful Improvements in Line-Casting Machines, of which the following is a specification.

This invention relates to improvements in line composing and type casting machines, and more especially to those of the linotype class which employ a pair of opposed relatively movable vise jaws to confine each line of matrices in an endwise direction when presented to the mold for the 15 casting of a line of type.

In machines of this class, it is often desirable to cast a slug or line without type faces or characters thereon, and heretofore such an operation has been accomplished 20 usually by setting up a line of blank matrices or so-called quads. This result, however, can also be obtained by bringing together and completely closing the vise jaws, the adjacent side of the movable jaw then 25 closing the mold opening.

The primary object of the present invention is to provide means for holding together the vise jaws for the casting of a blank line, thereby avoiding the necessity of setting up 30 quads or blank matrices, and this invention also provides automatically for the unlocking or release of the metal feed pump in those cases where the pump is provided with a lock to control its operation.

To these ends the invention consists in certain improvements, and combinations and arrangements of parts, all as will be herein-after more fully described, the novel features being pointed out particularly in the 40 claims at the end of the specification.

In the accompanying drawings:—Figure 1 is a front view of the casting mechanism of a machine of the linotype class embodying the present invention; Fig. 2 represents a 45 top plan view, partly in section, of the structure shown in Fig. 1; Fig. 3 is a rear elevation, partly in section, of the construction as shown in Figs. 1 and 2, the mold wheel and crucible or metal pot being re-

moved; Fig. 4 is a perspective view of a portion of the justifier mechanism embodying an improvement forming part of the present invention.

Similar parts are designated by the same reference characters in the several views. 55

In the present instance the invention is shown and will be described as applied to machines of the well known Linotype class, although it is to be understood that the invention is not restricted necessarily to machines of this particular type or to the precise construction shown, as equivalent constructions may be used to accomplish the same result and such structures will be included within the terms of the claims at the 65 end of the specification.

In the present instance each line of matrices is confined and held in an endwise direction when presented to the mold by the vise jaws 1 and 2, the right-hand jaw 1 being usually termed the fixed jaw in view of the fact that it is either fixed rigidly in position or has a very limited motion for the purpose of locking and unlocking the metal supply or feed pump, while the left-hand jaw 2 is commonly termed the movable jaw for the reason that it is adapted to be adjusted or set in different positions according to the varying lengths of the lines of matrices to be confined between the two 80 jaws. The mold 3 may be of the usual construction, providing an opening or slot 4 into which the metal is forced through the orifices 5 formed in the mouth-piece of the spout, the latter forming part of the crucible 85 or metal pot 6.

In the usual operation of machines of this class, each line of matrices is brought into a position between the opposed jaws by a slide 7 commonly termed the first elevator, 90 this elevator being movable vertically and carrying opposed jaws 8 at its upper end which receive the line of matrices from the line delivery mechanism and convey the line to a position between the vise jaws. The 95 crucible with its metal supply pump, the spout, and the mouth-piece having the orifices 5 therein may be of the construction com-

monly used, or of any other desired construction. Usually, the metal supply pump is operated at appropriate intervals to force metal into the mold to cast a slug by an arm 9, each descending movement of said arm operating the pump to supply a charge of metal in the usual way.

Most linotype machines employ a safety lock to prevent operation of the pump to supply metal except at the proper time. The lock 10 shown in the present instance is pivoted to a suitable stationary part of the frame at 11 and normally occupies a position beneath the lock or projection 12 on the arm 9 under the influence of a spring 13. Where a safety lock for the pump is employed, the right-hand vise jaw 1 is capable of a limited movement, and such movement is produced by the expansion of the usual wedge spacers during the justifying of the line of matrices. In the construction shown, this vise jaw 1 is adapted to be forced against a stop or set-screw 14 carried by a lever 15, the latter being pivoted at 16 on a suitable stationary part of the frame and its opposite end co-operates with the lock 10 whereby forcing of the vise jaw 1 against the stop 14 will rock the lever 15 in a direction to move the lock 10 clear of the locking projection 12, thereby permitting operation of the metal supply pump. Normally, however, the vise jaw 1 will not influence the lever 15 and hence the lock 10 will be in a position to prevent operation of the pump.

With such a construction, when it is desired to cast a blank line or slug without matrices, it is not only necessary to move the vise jaw 2 up against the jaw 1, but it is also necessary that the jaw 2 must exert at the proper time sufficient pressure on the jaw 1 to operate the lever 15 and thereby unlock the pump. It is difficult and dangerous for the operator to exert such pressure with the fingers during the casting operation, and according to the present invention automatic means is provided for accomplishing this result. Preferably, the justifier mechanism is utilized in carrying out the present invention, the justifier mechanism employing usually vertically movable rods 17 which in machines of this class are generally lifted automatically by spring pressure and they are pivotally connected at their upper ends to a justifier bar 18, this bar serving in the usual operation of the machine with matrices to force up the wedge spacers and thereby justify the line. According to the present invention, no matrices or spacers are used, but the motion of the justifier mechanism is utilized to force the movable jaw 2 against the jaw 1 with sufficient pressure to unlock the metal pump. To enable the justifier mechanism to per-

form this function, it is provided in the present instance with a cam or wedge 19 which may be fixed to one of the rods 17, and this wedge is adapted to co-operate with a suitable part of the movable jaw 2, the wedge in the present instance co-operating with the right-hand wall of an aperture 20 which latter is formed in the slide 21 to which the jaw 2 is attached. The dot-and-dash lines in Fig. 3 represent a setting of the movable jaw 2 for the casting of slugs from lines of matrices, and the dotted and full lines show respectively the movements of the two vise jaws under the influence of the wedge or cam on the justifier mechanism.

When the operator desires to cast a blank line or slug, it is only necessary to move the vise jaw 2 over against the vise jaw 1, either prior or subsequent to the descent of the elevator 7. The justifier rods 17 then rise, carrying the wedge or cam 19 into the aperture 20, thereby forcing the slide 21 and the jaw 2 attached thereto against the vise jaw 1 and locking the two vise jaws in direct engagement and also forcing the jaw 1 against the stop or set-screw 14 on the pump-controlling lever 15. The pump is then unlocked and may operate to inject a supply of metal into the mold to cast the blank line or slug, this being accomplished while the vise jaws are held or locked securely together and hence the escape of molten metal between them is avoided.

I claim as my invention:—

1. In a machine of the linotype class, the combination of a mold, fixed and movable vise jaws arranged in front of the mold, means for adjusting the movable jaw against the fixed jaw, a justifier arranged normally under the jaws to expand wedged spacers, and a head arranged on the justifier to engage the movable jaw to force and lock the same against the fixed jaw during the casting operation.

2. In a machine of the linotype class, the combination of a mold, a metal supply pump therefor having means for releasing the same, fixed and movable vise jaws, and means for forcing the movable jaw directly against the fixed jaw to close the opening in the mold and to operate the pump releasing means.

3. In a machine of the linotype class, the combination of a mold, a pair of vise jaws adapted to confine a line of matrices between them and capable of being brought together into direct contact, justifier mechanism for expanding the spacers in a line of matrices, and means operative automatically by the justifier mechanism for forcing one of said jaws against the other when the same are brought together without matrices between them.

4. In a machine of the linotype class, in

combination; a mold, a pair of vise jaws, justifier mechanism for driving up the wedge spacers, and a taper or wedge head mounted on said justifier mechanism and adapted to drive one of said jaws against the other and hold it during the casting of the slug.

In testimony whereof I have hereunto set

my hand in presence of two subscribing witnesses.

WILLIAM E. BERTRAM.
